UNITED STATES PATENT OFFICE.

JAMES BOWEN, OF MANHEIM, PENNSYLVANIA, ASSIGNOR TO BOND FOUNDRY & MACHINE COMPANY, OF MANHEIM, PENNSYLVANIA, A CORPORATION OF PENNSYLVANIA.

CASTER.

Application filed December 19, 1924. Serial No. 756,920.

The object of this invention is to improve the construction of casters, particularly adapted for use on trucks.

Casters of this type must be substantial and so designed that they will swivel readily under heavy loads, while supporting the loads properly at all times.

In the accompanying drawings:

Fig. 1 is a side view, showing the upper portion of the caster in section;

Fig. 2 is a sectional plan view on the line 2-2, Fig. 1;

Fig. 3 is a front view of the caster;

Fig. 4 is a detached side view of one of the rollers;

Fig. 5 is a perspective view of one of the rollers;

Fig. 6 is a detached sectional view of the base of the caster;

Fig. 7 is a detached sectional view of the body portion of the swivel section of the caster;

Fig. 8 is a plan view of one-half of the retainer for the rollers; and

Fig. 9 is a sectional perspective view of a portion of the retainer.

The base member 1 of the caster is perforated, as shown by dotted lines, to receive bolts, which attach the base to the frame of a truck. The base has a central depression 2, in which is a tapered opening 3. Depending from the periphery of the base is a deep flange 4, which encloses the body portion 5 of the swivel member 6 of the caster. The member 6 is forked, as at 7, to receive a supporting wheel 8, which is mounted on a sleeve 9 that is carried by a bolt 10. The body portion 5 has a tapered projection or boss 12, which extends into the tapered opening 3 in the base 1. A king bolt 11 extends through an opening in the tapered portion 12. The shank of the bolt is squared at 13 under the head 14 and fits a squared portion of the said opening so that the bolt turns with the swivel portion 6 of the caster. The head 14 of the bolt is located in the depression 2 of the base 1 and a washer 15 is located under the head and extends over the base of the depression, holding the swivel portion 6 to the base 1. On the threaded end of the bolt is a nut 16. This construction prevents the king bolt from becoming loose.

From the foregoing description, it will be clear that the swivel member can move with respect to the base member about a vertical

axis. One of these members is provided with a single annular raceway 24 and the other of the members is provided with two annular raceways 17 and 18 spaced apart. Preferably the single raceway is on the base member and the two spaced raceways are on the swivel member, but I do not necessarily limit myself in this respect.

In accordance with my invention the aforesaid raceways are so shaped and so located that their lines of intersection with a vertical radial plane can be extended a considerable distance past the swivel axis without intersecting each other. This is illustrated in Fig. 1 wherein the line *w-w* extending through the raceway on the base member and the line *y-y* extending through the two raceways on the swivel member intersect each other at a point considerably beyond the vertical swivel axis.

Located between the two plates and engaging the respective raceways are bearing rollers 20. Each roller has a relatively large central portion 23 engaging the single raceway 24 on the base member and has two trunnions 21 and 22 respectively engaging the two raceways 17 and 18 on the swivel member. It will be observed that the portion 23 of the roller extends into the groove 19 between the two raceways 17 and 18 and is adapted to travel freely in this groove without contacting with the swivel member.

Preferably the raceway 24 is flat and the raceways 17 and 18 are beveled. In this case the line *w-w* is horizontal and the line *y-y* is inclined so as to intersect at the point *w* the horizontal plane extending through the axes of the rollers. This point of intersection is at the vertical swivel axis. The two trunnions 21 and 22 are tapered uniformly and in the same direction so as to give true rolling contact with the raceways 17 and 18. When the several raceways are shaped and located as described the central portion 23 of each roller is cylindrical, being of uniform diameter throughout so as to engage the flat raceway 24.

With the construction described the tapered trunnions cause the rollers to travel in a circular path inasmuch as they have true rolling contact with their respective raceways. A true theoretical rolling contact is not secured at the raceway 24 and this is avoided in order to eliminate, or at least minimize, the tendency which would other-

wise exist for the load to gradually crowd the rollers outward. It will be obvious that as the angle between the line $w-w$ and $y-y$ is reduced this tendency for the rollers to work outward is correspondingly reduced.

In order to prevent any possible endwise movements of the rollers annular flanges 29 and 30 are provided on one of the members preferably on the swivel member as shown. 10 The ends of the rollers are made convex so that the friction on the flanges 29 and 30 is reduced to a minimum.

For spacing the rollers, I provide a device which is so constructed and so located that 15 it does not interfere with the engagement between the ends of the rollers and the said flanges 29 and 30. This device comprises a flat plate which is located between the trunnions 21 and 22 and the raceway 24 and 20 which is provided with apertures through which the central parts 23 of the rollers project. The plate is provided with depending webs 26 and 27 which extend between the trunnions of the rollers as shown.

25 A ball bearing is preferably provided to take the side thrusts on the caster. The inner raceway 31 is formed on a depending flange of the base that surrounds the opening 3, and an outer raceway 32 is formed on 30 the inner surface of the annular raceway 18 of the body portion 5. Balls 33 are located between the two raceways, as shown, and take the lateral thrust of the caster. The peripheral flange 4 of the base 1 encloses the 35 mechanism, making the caster substantially dust proof.

The annular channel 19 forms a receptacle for lubricant, as does the space occupied by the balls. The channel can be supplied with 40 grease, or other lubricant, through a valved cup 34.

I claim:

1. The combination in a caster, of a supporting wheel, a base member, a swivel member connected with the wheel and movable with respect to the base member about a vertical axis, the base member being provided with a flat annular raceway and the swivel member being provided with two spaced beveled annular raceways, a series of rollers between the two members, each roller having a relatively large central cylindrical portion engaging the first said raceway and travelling freely between the second said raceways and also having two trunnions respectively engaging the second said raceways and so tapered as to have true rolling contact therewith, and a spacer for the rollers comprising a flat plate located between the roller trunnions and the base member and have apertures through which the central parts of the rollers project.

2. The combination in a caster, of a supporting wheel, a base member, a swivel member connected with the wheel and mov-

able with respect to the base member about a vertical axis, the base member being provided with a flat annular raceway and the swivel member being provided with two spaced beveled annular raceways, a series of rollers between the two members, each roller having a relatively large central cylindrical portion engaging the first said raceway and travelling freely between the second said raceways and also having two trunnions respectively engaging the second said raceways and so tapered as to have true rolling contact therewith, and a spacer for the rollers comprising a flat plate between the roller trunnions and the base member and have apertures through which the central parts of the rollers project.

3. The combination in a caster, of a supporting wheel, a base member, a swivel member connected with the wheel and movable with respect to the base member about a vertical axis, the base member being provided with a flat annular raceway and the swivel member being provided with two spaced beveled annular raceways, a series of rollers between the two members, each roller having a relatively large central cylindrical portion engaging the first said raceway and travelling freely between the second said raceways and also having two trunnions respectively engaging the second said raceways and so tapered as to have true rolling contact therewith, and a spacer for the rollers comprising a flat plate between the roller trunnions and the base member and have apertures through which the central parts of the rollers project.

4. The combination in a caster, of a supporting wheel, a base member, a swivel member connected with the wheel and movable with respect to the base member about a vertical axis, the base member being provided with a flat annular raceway and the swivel member being provided with two spaced beveled annular raceways, a series of rollers between the two members, each roller having a relatively large central cylindrical portion engaging the first said raceway and travelling freely between the second said raceways and also having two trunnions respectively engaging the second said raceways and so tapered as to have true rolling contact therewith, and a spacer for the rollers comprising a flat plate between the roller trunnions and the base member and have apertures through which the central parts of the rollers project.

5. The combination in a caster, of a base provided with a flat annular raceway; a swivel section pivoted to the base and hav-

ing two annular beveled raceways; a series of rollers located between the base and the swivel section, each roller having a main cylindrical portion and tapered trunnions, said trunnions resting upon the beveled raceways, the base having a central depending flange forming a ball raceway; and a series of balls between said depending flange and the side of the inner beveled raceway 10 of the swivel section.

6. The combination in a caster, of a base having a central depression in which is a central opening, said base having an annular flat raceway; a swivel section; a wheel carried thereby, said swivel section having a body portion located under the base and having a central boss extending through the central opening in the base; a bolt extending through the said boss and prevented 20 from turning therein, said bolt having an enlarged head overlapping the bottom of the depression of the base; a nut on the bolt; a series of balls between the base and the swivel section for taking the lateral thrusts 25 upon the caster; and a series of rollers be-

tween the base and the swivel section for carrying the load.

7. The combination in a caster, of a base having a central depression with an opening therein, a deep annular flange at its periphery and a flat raceway between the flange and the depression; a swivel section; a wheel carried thereby, the body of the swivel section having a central boss extending into the opening in the base; a king bolt connecting the swivel section and the base, the body of the swivel section having two annular raceways spaced apart by a deep channel, said raceways being beveled; a series of rollers, each roller having an enlarged portion bearing against the flat raceway of the base and tapered trunnions bearing on the two raceways of the body portion; means for spacing the rollers; and a ball bearing located between the base and 40 the body of the swivel section for taking the side thrusts of the caster, the deep flange of the base enclosing the mechanism of the caster. 45

JAMES BOWEN.
